UNITED STATES PATENT OFFICE.

ALBERT THODE, OF HAMBURG, GERMANY.

MAXIMUM CUT OUT.

1,411,389.

Specification of Letters Patent.

Patented Apr. 4, 1922.

Application filed August 31, 1915. Serial No. 48,368.

(GRANTED UNDER THE PROVISIONS OF THE ACT OF MARCH 3, 1921, 41 STAT. L., 1313.)

To all whom it may concern:

Be it known that I, ALBERT THODE, a subject of the Emperor of Germany, residing in Hamburg, Germany, Sonnistr. 17/18, have 5 invented certain new and useful Improvements in Maximum Cut Outs, of which the following is a specification.

This invention relates to improvements in electrical apparatus and particularly to over 10 load circuit breakers or maximum cut-out switches.

One object of this invention is to provide an apparatus of this kind which is simple in construction and effective and reliable in 15 operation.

My improved switch is provided with main and auxiliary contacts, and is so arranged that it is impossible to close the circuit if at the time there is an excessive current 20 rent therein, even though the operator holds the handle of the switch in closed position.

Other objects of the invention will appear as the description proceeds; and while herein minute details of the invention are 25 described, the invention is not limited to these since many and various changes may be made without departing from the scope of the invention as claimed.

In the accompanying drawing showing, 30 by way of example, one of many possible embodiments of the invention,—

Figure 1 is a side view;

Fig. 2 is a plan, and

Fig. 3 is a section taken on the line A—B 35 of Figure 2.

Similar letters refer to similar parts throughout the several views.

The handle b^1 is secured to the shaft b journaled in the casing of the cut-out. A 40 gear or toothed wheel a is loosely mounted on the shaft b and is provided on its upper side with a series of ratchet teeth. These teeth co-operate with other conveniently shaped ratchet teeth on the adjacent end of 45 a boss c , mounted shiftably on the shaft b . The teeth on the gear a and the boss c constitute a clutch-coupling. If the same is thrown into gear, the boss c engages at each 50 turning of the handle b^1 the gear a . This gear a also engages a rack d (Fig. 2) forming a part of the switching-device d^1 , which is provided at one end with the contact e

which, when shifted to the left (of Figure 2) by a turning of the handle, engages the contacts e^1 and e^2 . The other end the switching-device d^1 is provided with an insulating piece e^3 which, on turning the handle b^1 for the purpose of breaking the circuit, enters between the auxiliary contacts e^3 and e^4 , controlled by compression springs e^6 , and 55 separates them from each other, whereas these auxiliary contacts will engage each other if the switching device d^1 is shifted in the opposite direction for closing the circuit by bridging the contacts e^1 and e^2 by e . 60 The arrangement is such that during this movement the contacts e^3 and e^4 engage each other before the contact e engages the contacts e^1 and e^2 ; and inversely, when the switching member is moved to the right (of 65 Figure 2) the circuit is broken at e^1 and e^2 prior to being opened at e^3 and e^4 .

If the clutch-coupling is thrown into gear so that the gear a and the hub c engage each other, the switching-device d^1 can be brought 70 into the closing position by turning the handle b^1 , whereby a spring h (Fig. 2) is compressed. The spring h may be applied in any convenient manner, for instance, between an abutment h^1 and the end of the 75 open central portion of the switching device d^1 . In the closing position a pawl g , journaled at g^1 on the frame and actuated by a spring or its own weight, comes into engagement behind a shoulder g^2 (Fig. 1) 80 on the switching device d^1 and maintains the latter in the closing position.

The gear a and hub c when coupled together by relative engagement may be uncoupled either by an electro-magnet k with 85 its armature k^1 , or by a turning of the handle b^1 for the purpose of breaking the circuit. For this purpose the boss c is secured to a lever f by a tenon f^1 fastened to it with sufficient play, which lever f is journaled at 90 f^2 in the frame. The action of gravity holds the lever f and boss c depressed, so that springs need not be used unless desired. The lever f is provided at its inner end with the arm f^3 and the arm f^4 transverse thereto 95 (Fig. 2). Under the arm f^4 is located a lever k^2 journaled on the frame at k^3 (Fig. 3) and secured at one end to the armature k^1 of the electro-magnet and adapted at its 100

other end to engage beneath the arm f^1 and the pawl g . The arm f^3 also engages under the pawl g and is adapted to lift the latter.

If the armature k^1 of the electro-magnet be actuated the lever l^2 moves upwards and thereby lifts the pawl g out of engagement with the locking shoulder g^2 of the switching-device d^1 and raises also the lever f , whereby the ratchet teeth of the boss c are lifted out of engagement with the ratchet teeth of the gear a . The gear a secured loosely on the shaft b is thereby disengaged, so that the switching-device d^1 is brought into the off-position under the action of the compressed spring h . Consequently any increase of the strength of current in the electro-magnet k beyond a determined limit will produce the automatic breaking of the current. The armature k^1 is yieldably held in raised position by the spring m tensioned between a perforated lug k^4 on the armature and a bracket m^1 mounted on the frame of the switch.

It is equally possible to operate my device by hand. If the handle b^1 is turned for the purpose of breaking the circuit, the slanting surfaces of the ratchet-teeth on the front of the gear a will raise the coupling boss c , whereby the same result is obtained as by lifting of the lever f by the attraction of the armature k^1 of the electro-magnet. The pawl g is then thrown out of engagement and the switching device d^1 springs back into the off-position.

The operation of the cut-out is as follows: If the handle b^1 is turned for the purpose of switching in, the switching-device d^1 is in the first place moved so far that the circuit is closed at the auxiliary contacts e^3 , e^4 , which are located in the circuit of the electro-magnet k parallel to the principal contacts e^1 and e^2 . If the strength of the current be normal, the coupling between the handle and the switching device remains unaltered and the closing of the circuit takes place at the principal contacts e^1 and e^2 . If the strength of the current should rise excessively the disengagement is produced automatically, by the attraction of the armature, the raising of the lever g , and the consequent release of the switching device d^1 and its unswitching movement under the action of the spring h . If switching-off is to be done by hand, the coupling between c and a can be opened by a simple turning of the handle b^1 in the opposite direction and switching-off takes place in the same manner as if it had been effected by the electro-magnet. But if in the moment of switching-off in an excessive current should be present, the armature will be attracted as soon as the circuit is closed at the auxiliary contacts e^3 , e^4 , whereby the coupling between c and a is disengaged, so that any further shifting of the switching-device d^1 and with it any

switching-in of the principal contacts e^1 and e^2 can no longer be accomplished by turning the handle b .

What I claim as my invention and desire to secure by United States Patent is:—

1. In a maximum cut-out, the combination of a pair of main contacts; a switching device normally pressed away from said contacts and adapted to electrically connect them; a handle member; a pair of ratchet members, one operatively connected with said device and the other adapted to be driven in either direction by said handle member, said ratchet members being provided with inter-engaging ratchet teeth whereby when said handle member is moved in one direction the ratchet members are separated, and when driven in the other direction the switching device is moved against said contacts; a pawl adapted to hold said device against said contacts; a tripping device adapted to release said pawl and to separate said ratchet members and to be actuated by the separation of said members to release said pawl; and an electric actuated device adapted to cause said tripping device to separate said ratchet members or release said pawl.

2. In a maximum cut-out, the combination of a pair of main contacts; an electro-magnet connected therewith; a pair of flexible auxiliary contacts normally in contact with each other; a switching device provided with a rack and a shoulder and adapted when moved in one direction to electrically connect said main contacts and when moved in the other direction to electrically separate said auxiliary contacts; a handle shaft; a toothed wheel loosely mounted on said shaft and meshing with said rack and provided with click-teeth; a boss constrained to rotate with said shaft and provided with click-teeth intermeshing with said first named teeth and adapted to cause the separation of said hub and wheel when the handle is rotated in one direction and to cause the wheel to rotate and close said head against said main contacts when the handle is rotated in the other direction; a pawl adapted to engage said shoulder and hold said head closed against said main contacts; a tripping lever adapted to raise and be raised by said hub and adapted to raise said pawl; an armature-lever adapted to raise said tripping lever; and an armature on said armature-lever and influenced by said electro-magnet.

3. In a maximum cut-out, the combination of a pair of main contacts; an electro-magnet in series with the contacts; a pair of flexible auxiliary contacts electrically connected to the main contacts respectively, and adapted to contact each other; a switching device provided with a contact head adapted to engage and connect said main contacts,

with an insulating piece adapted to engage and separate said auxiliary contacts, and with a shoulder; a rack on said device; a handle shaft; a toothed wheel loosely mounted on said shaft and engaging said rack and provided with ratchet teeth; a ratchet boss 5 slidably mounted on said shaft and held against rotation relative thereto and provided with teeth engaging said ratchet teeth; a pawl adapted to engage said shoulder and hold said head in engagement with said main contacts; a spring tending to move said device away from said main contacts; 10 a tripping lever engaging said hub and engaging under said pawl and adapted to raise 15 or be raised by said hub and adapted to raise said pawl; an armature lever having one end engaged under said tripping lever; and an armature carried on the other end of said armature lever and near said electro- 20 magnet.

In witness whereof I have hereunto signed my name this 3rd day of August, 1915, in the presence of two subscribing witnesses.

ALBERT THODE.
